UNITED STATES PATENT OFFICE.

FREDERIC GEILINGER, OF WASHINGTON, DISTRICT OF COLUMBIA.

DESIGN FOR AN AUTOMOBILE-LOCK.

56,135.

Specification for Design.

Patented Aug. 24, 1920.

Application filed March 18, 1920. Serial No. 366,997. Term of patent 7 years.

To all whom it may concern:

Be it known that I, FREDERIC GEILINGER, a citizen of the United States, residing at Washington, in the District of Columbia, have invented a new, original, and ornamental Design for an Automobile - Lock, of which the following is a specification, reference being had to the accompanying drawings, forming a part thereof.

The figure is a perspective view of the automobile lock, showing my new design.

I claim:

The ornamental design for an automobile lock, as shown.

FREDERIC GEILINGER.

Witness:

BENNETT S. JONES.
